FILLER FOR CARTONS

John L. Dusseault, Chelmsford, Mass., assignor to
Patent Protection Corporation, Lowell, Mass.,
a corporation of Massachusetts

Application August 19, 1950, Serial No. 180,334

2 Claims. (Cl. 229—14)

1

This invention relates to cartons of fibre board, paper board or the like for use in shipping comparatively heavy, boat-shaped objects.

Heretofore it has not been considered practical or possible to ship an object as large or as heavy as a ten or twenty foot outboard motor-boat in a carton made entirely of paper board. Usually, boats, bathtubs, etc., have been shipped enclosed in a wooden crate or in a cardboard carton which contains an interior wooden crate structure as a reinforcement.

Disadvantages of enclosing an article to be shipped in a wooden structure are that the structure usually cannot be shipped or stored in knock-down condition, the assembly of the crate requires wood-working tools, installation time and factory space, the crating structure is heavy and adds to the freighting charges and the outside dimensions of the packaged article are increased because of the wooden framework.

I have discovered that such articles can be shipped safely and securely in a carton made entirely of paper board, if constructed according to my invention, without the use of any interior or exterior wood frame reinforcement. I provide a carton in the form of a six-walled rectangular container, preferably of double walled corrugated paper board and provide integral flanges on each free edge of the walls, which are turned inward, to strengthen the carton. To position and cushion the boat-shaped article within the container, I provide substantially wedge-shaped fillers preferably of similar double-walled, corrugated paper board and located at each end of the container.

The cooperative action of my new fillers with the walls and corners of the container not only retains the article in position, but prevents rupture of the container by cushioning any movement of the article in the container, prevents crushing of the container when stacked, by distributing the load, and eliminates the need for pads, etc., to protect the surface of the article from damage.

My container and fillers are creased and cut into flat blanks of paper board and can be shipped or stored flat until needed. The filler blanks are preferably creased transverse to the corrugations of the board to provide more yieldability without loss of strength. Large numbers of my container and filler blanks can be stored in a boat factory in a small space whereas a large space is required to store the equipment and material necessary to make wood crates or wood reinforcements for cardboard cartons.

2

The container of my new carton is assembled by staying the edges of the cover walls and unfolding the tubular body of the same in a well known manner and the fillers are simply folded into substantial wedge shape on their crease lines and inserted between the bow and stern of the boat and the ends of the container. When assembled and packed, the tare weight of my new carton is only about one-tenth that of conventional boat crates or cartons, thus providing a large reduction in shipping cost. Similarly, the outside dimensions of my carton, since there is no wood reinforcing structure within, is less than the conventional type, thus giving rise to a saving of space and in cost of shipping.

Upon arrival at a factory outlet, the covers of my carton can be removed, and, if desired, the tubular body of the container can be stored flat, while the article contained therein is displayed. 20 Upon reshipping to a purchaser, the same covers and container may be reinstalled. This is in contradistinction to a boat shipped in a wooden crate where the crate must be removed and usually damaged before the article can be displayed. 25 Ordinarily the parts of such a crate cannot be used again due to damage or loss.

My carton may be used for shipping scows with blunt ends, sail boats with abbreviated keels, motor boats with a rounded bow and a blunt stern, canoes with pointed ends, or, in fact, any generally boat-shaped article. My fillers can be adapted to the particular shape of either bow or stern and in each case have a double thickness of material in contact with the boat, backed up by an air space into which the doubled material can yield. In the case of broad beamed boats, I prefer to removably mount two transverse wooden cleats across the gunwales and to bind the outside of the carton with steel strapping at the cleats so that the carton may be lifted by a crane or the like without losing its rigid rectangular shape.

The principal object of my invention is therefore to provide a shipping carton of corrugated paper board or the like with end fillers of similar material in which a heavy boat-shaped article may be shipped without the necessity of an interior framework of reinforcing material.

Another object of my invention is to provide end fillers of corrugated paper board so folded as to form an air space into which the filler panel under rupture pressure may yield and so folded as to transfer crushing and rupture pressures to the walls and corners of the container.

55 A further object of my invention is to provide

a container and fillers for the same, all of which can be shipped or stored in knock-down condition and can be assembled for use without mechanical equipment or expert knowledge.

Other objects of the invention have been outlined above and will appear in the following description:

In the drawings, Fig. 1 is a side elevation in section of the preferred form of my carton on line 1—1 of Fig. 2.

Fig. 2 is a plan view in section of the carton shown in Fig. 1 on line 2—2 of Fig. 1.

Fig. 3 is an end view in section on line 3—3 of Fig. 2.

Fig. 4 is an end view in section on line 4—4 of Fig. 2.

Fig. 5 is an isometric view of the blank from which my preferred form of corner filler is made.

Fig. 6 is an isometric view of the blank from which my preferred form of end filler is made.

Fig. 7 is a plan view in section on line 7—7 of Fig. 8, showing a modified form of container and filler used for a canoe or the like.

Fig. 8 is a side elevation in section on line 8—8 of Fig. 7 of the device shown in Fig. 7.

Fig. 9 is a side elevation in section on line 9—9 of Fig. 10, showing a further modification of my new carton for use with a dinghy, scow or the like.

Fig. 10 is a plan view in section on line 10—10 of the carton shown in Fig. 9.

As shown in Figs. 1 to 6, the preferred form of my new carton is capable of carrying a boat-shaped article of substantial size and weight such as the outboard motor boat O. My carton has been used successfully to ship outboard boats of over fifteen feet in length and centreboard sailboats each weighing between three and four hundred pounds and made of material such as plastic impregnated "Fibreglass." It may also be used for boat-shaped articles of other materials such as aluminum or wood.

The container A, of my new carton, has four side walls 10, 11, 12, and 13, a top wall 14 and a bottom wall 15, thus forming a six walled rectangular box. The side walls are suitably creased, cut or stayed at the corners 16, 17, 18, and 19, in a well known manner, in order that the four walls 10, 11, 12 and 13 of tubular body 20 of container A may be shipped or stored flat and unfolded when needed. I provide integral inturned edge flanges 21 on the upper edge of each side wall and integral edge flanges 22 on the lower edge of each wall of 20 to add strength to the container when used for a boat-shaped article of comparatively broad beam such as O. I also provide integral inturned edge flanges 23 on top wall 14 and integral inturned edge flanges 24 on bottom wall 15, which overlie the side walls and also add strength to the container A.

The material from which the container and fillers of my new carton are made is what I call double walled corrugated paper board. The double wall preferably consists of A and C flute, 100% Kraft, 0.023 outer-middle-inner liners with 0.009 Kraft corrugating medium. The crease lines, upon which the walls, flanges and panels are folded to form a fibrous hinge, indent only the inner liner and the creases are transverse to the corrugations in the corrugating medium. Rupture and crushing pressure or impacts are thus passed along the corrugations to other parts of the carton rather than causing the paper board to break along a corrugation.

In general the fillers provided in my new carton comprise a strip of double walled corrugated

paper board creased transversely to the corrugations and bent through interior angles, one of which is a right angle, into five panels with at least two panels overlying other panels. The folded filler thus is generally wedge shaped with at least two adjacent panels forming a right angle to fit an interior corner of the rectangular container and at least two overlying panels arranged to contact the portion of the boat-shaped article that it is desired to retain in position and cushion against movement. In all of my fillers, whether right triangular or trapezoidal in cross section, the panels are so folded as to define an air space thus providing room for the two overlying contact panels to yield and bend under stress. When yielding, the impact upon the contact panels is passed along by the corrugations to other panels of the filler and thence to the walls and corner flanges of the container where it is absorbed and whence the contact panels are caused to rebound due to the inherent resiliency of the corrugated material.

In the preferred form of my carton, I use an end filler C at the stern 30 of O and a pair of corner fillers D at the rounded bow 31 of O. End filler C is formed from a strip or blank 49, shown in Fig. 6, and formed of double walled paper board with longitudinal corrugations as at 41. Transverse creases at 42 are provided to divide the blank into panels 43, 44, 45, 46, 47 and 48, in which condition it may be stored or shipped ready for folding into the trapezoidal form shown in Figs. 1 and 2. The width of strip 49 is equal to the distance between side walls 10 and 12 of container A in order that it may closely abut on walls 10 and 12 thereof, and panel 46 forms right angles with panels 47 and 45 which closely fit the right angles formed by side wall 11 with flanges 21 and 22, top wall 14 and bottom wall 15. The diagonal panels 48 and 44 overlie each other to give a double thickness of material in contact with stern 30 of boat O which will yield into air space 49, as shown in dotted lines, in Fig. 1 when boat O is subject to longitudinal endwise motion. It should be noted that the substantial flat area of the stern 30 in contact with the flat panel 44 tends to prevent appreciable sidewise movement of the boat O in the container A.

At D, I show my preferred form of corner filler for use with a broad beamed boat such as O. As shown in Fig. 5, D is formed from a strip or blank 59 of double walled paper board having corrugations 51 which extend longitudinally thereof, as in C. Creases at 52, divide D into panels 53, 54, 55, 56, 57, 58 and 59, the strip being shipped or stored flat and folded as shown in Fig. 2, into a wedge shape of right angular cross section. Panels 59 and 53 overlie panel 56 to give a double thickness of material along diagonal 61 in tangential contact with a central point 60 on the upper portion of bow 31 of boat O. Panels 58 and 54 meet and abut each other to form a web 62 of double thickness, thus providing a reinforcement for the diagonal 61 intermediate of its length. Web 62 is preferably perpendicular to diagonal 61 and extends to the adjacent corner of container A such as 19 or 18. As shown in Fig. 4, the surface of the boat O contacts filler D only at point 60 since the bow curves downwardly and away therefrom, thus preventing abrasion or other damage to the boat paint or structure. The boat O is packed in container A, with a space of several inches at 64 between the tip of the bow 31 and the adjacent wall 13, thus providing room for the boat to move

longitudinally without rupturing the container. As shown in dotted lines in Fig. 2, such movement of the boat O causes the contact point 60 to bend the diagonal 61 of the primary right triangle 65, and to bend diagonal 59 of the larger secondary right triangle 66 of the pair of secondary right triangles 66 and 67 contained in 65, into the air space 68 of 66. After yielding into space 68, diagonals 61 and 59 rebound into their normal retaining position, having absorbed the impacts and transferred such impacts to other panels of strip D and to the adjacent walls of container A.

Sidewise movement of the boat O also causes contact point 60 to bend 61 and 59 into 68 and the impact is passed along to the adjacent side wall 10 of container A and absorbed thereby.

For convenience in hoisting my new carton by a crane for loading, unloading, and stacking, I provide two or more transverse cleats 80, 81, of wood or the like, which extend transversely of the container, intermediate thereof, on opposite sides of the centre of gravity. Cleats 80, 81 rest on the gunwales 82 of O and are provided with holes 83 at each end, arranged to register with the oar lock holes 84 of boat O and to be removably connected thereto by bolts 85 or other suitable means. On the exterior of the container I provide metal girth straps 86, 87, drawn taut in a well known manner and located opposite each cleat and may also provide a longitudinal girth strap 88 for additional reinforcement, as shown in Fig. 3. The ends of each cleat 80, 81 abut on each side wall such as 10 or 12 of A and thus are useful in maintaining the rigidity of the carton.

In Figs. 7 and 8, I show a modification of my device for use with a canoe M or similar boat-shaped article having both ends rounded or pointed. The container F is six walled having an open tubular body with four hinged side walls 101, 102, 103, and 104, and closure walls at each end 105 and 106. For reasons of economy and ease of manufacture, I find that boat-shaped articles of narrow beam are best enclosed in an elongated horizontal tube such as F, rather than a low walled vertical tube such as 20, although either can be used.

I prefer to use a pair of corner fillers such as D at each end of container F as shown at the bow 107 of M. However, I may use a corner filler such as G as shown at the stern 108 of M, which comprises a strip 99 of double walled corrugated paper board bent into wedge or right triangular shape. As indicated, G is bent at crease lines which are transverse to the corrugations through three interior angles 113, 114 and 115, 115 being a right angle, to form five panels 109, 110, 111, 112 and 310 with panel 109 overlying the hypotenuse or diagonal panel 112 and panel 310 overlying panel 110. Panels 310 and 111 rest against walls 105 and 102 of F and the width of the strip 99 is equal to the distance between walls 101 and 103 of F to make a snug corner fit. An air space 116 is defined by the five panels of G and provides room for panels 112 and 109 to bend and yield under pressure or impact from a single contact point such as 117 on stern 108 of M. Space is also provided at 119 and 120 between the tip of stern 108 and wall 105 and the tip of bow 107 and wall 106 to enable M to move without rupturing container F. It is obvious that all four corner fillers would ordinarily be of the same type and I find the type shown at D to be preferable to the type shown

at G. Cleats such as 80 and straps such as 86 are used to add reinforcement to container F, when the article such as M is of comparatively broad beam.

In Figs. 9 and 10 a further modification is shown in which a container L similar to A is used for a boat shaped article N with blunt ends and broad beams such as a dinghy, scow or the like. The short vertical tubular body 210 of container L has four side walls 204, 205, 206, 207, an upper wall 209 and a lower wall 208, each wall being provided with inturned flanges for strengthening purposes. End fillers H, similar to C, are used between the bow 312 and wall 205 and between the stern 311 and wall 207. Two or more transverse cleats 213, removably attached to the gunwales 214 of N, by bolts 216 and a girth strap 215 are also used in the manner and for the purpose above described.

As in end filler C above, an air space 220 is provided in H into which two overlying diagonal panels such as 221, 222, of H may yield to absorb impact and pass the impact along to other panels and walls of the container.

It should be noted that all of my fillers whether trapezoidal as in C and H, right triangular as in G, or right triangular with inner right triangles as in D are characterized by the following features. Each is formed from a blank of double walled corrugated paper board which is creased transversely of the corrugations and bent at the creases into a substantial wedge shape. Each has at least five panels, with the oblique or diagonal surface, presented to the boat-shaped article, having two overlying panels which are free to slide upon each other and arranged to yield and bend into an air space defined by the five panels. Each also has at least two other panels which overlie and form a web of double thickness between the oblique or diagonal surface and a corner of the container. The oblique panels of double thickness are thus reinforced by a web of double thickness which in turn is reinforced by the corner of the container at which the flanges of the tubular body and/or closure members are located.

I claim:

1. A corner filler to cushion the rounded end of a boat-shaped article from movement in a rectangular container, said filler comprising an elongated strip of corrugated paper board or the like, bent at spaced transverse lines into a plurality of fibrous hinged panels which define a primary right triangular air space divided into two secondary right triangles, each of the opposite end panels of the strip overlying a portion of the hypotenuse panel of the primary triangle to present an hypotenuse panel of double thickness of paper board, each hypotenuse panel of the secondary triangle being positioned at right angles to each other and the intermediate panels of each secondary triangle meeting to form a central web of double thickness extending perpendicularly from the hypotenuse of the primary triangle to the right angular corner of said filler.

2. A filler, for use in the interior of rectangular cartons, said filler comprising a continuous elongated strip of corrugated paperboard material bent transversely of its corrugations to form an hollow enclosed figure, said figure having two walls of a single thickness of said material, each positioned at right angles to the other; having a third wall positioned obliquely to said right angularly positioned walls; having all of its walls, except said two right angularly positioned walls

formed of a double thickness of said material and having a web of a double thickness of said material, extending from an intermediate line on said oblique wall to the meeting line of said right angularly positioned walls.

JOHN L. DUSSEAUULT.
